His Attorney

UNITED STATES PATENT OFFICE.

WILLIAM W. BOWMAN, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

CASH REGISTER.

Application filed January 8, 1925. Serial No. 1,198.

This invention relates to cash registers, and more particularly to improvements in impression hammers of the kind used in machines of the type shown and described in 5 Letters Patent of the United States, No. 1,311,884, issued to Frederick L. Fuller, August 5, 1919, and a co-pending application by Bernis M. Shipley Serial No. 610,273, filed January 2, 1923.

10 The principal object of this invention is to provide mechanism to prevent rebound of spring-actuated printing hammers.

With this and incidental objects in view, the invention consists of certain novel features of construction and combinations of parts, the essential elements of which are set forth in appended claims and a preferred 15 form of embodiment of which is hereinafter described with reference to the drawings 20 which accompany and form a part of this specification.

Of said figures:

Fig. 1 is a side elevation of the printing hammers and their associated mechanism.

25 Fig. 2 is an enlarged detail side view of a part of the mechanism shown in Fig. 1.

Fig. 3 is a plan view of the mechanism shown in Fig. 1.

In general.

30 In impression hammer mechanisms of the type herein disclosed, each hammer is actuated by a powerful spring, which when released forces the hammer against the type carriers with a sudden blow. In the above mentioned co-pending application, when the hammer falls back to its normal position it strikes its actuator and stretches the driving spring, which causes the hammer to rebound and in some instances this rebound is sufficient to cause a second impression to be made. In the present application an unyielding member is provided to prevent this rebound and thereby prevent the hammer 35 from striking the type carriers the second time.

Impression mechanism.

In machines of a type to which the invention is shown applied, a record 30 (Fig. 1) is 50 placed upon a table 31. Any number of impression hammers 34 may be provided. In the present application seven are shown,

each of which is adapted to carry the record and a ribbon 33 against type carriers 32, thereby taking an impression therefrom. 55 An actuator 35 is provided for each hammer. All of the actuators are loosely mounted on a stud 36 mounted in the frames 37. Each actuator has an extension 38, which is 60 adapted to engage a stud 39 mounted on the corresponding impression hammer 34. A spring 47 stretched between a shaft 46 and a stud 45 on the actuator 35, normally tends to rock the actuator in a counter-clockwise direction against a yoke 50. The yoke 50 has downwardly extending arms 51 and 52. The arm 51 has mounted thereon a stud 55, which is engaged by a link 56, (Fig. 2) pivoted to the lower end 57 (Fig. 1) 70 of a bell crank 58. The upper arm 59 of the bell crank 58 is adapted to engage a cam 60 on a shaft 61, which may be driven in any suitable manner.

In the above mentioned patent and application the shaft 61 is driven from the main operating shaft of the machine, which is in turn driven by a motor.

The cam 60 is slidably mounted on the shaft 61 and is provided with two high 80 points 62. One of the high points extends across the full width and the other only half way across the cam. The purpose of this construction is to provide means to control the hammers for taking one or two impressions. This mechanism forms no part of the present invention and no further description is thought necessary. A complete disclosure and description can be had by referring to the above mentioned co-pending 85 application.

When the cam 60 is rotated in a counter-clockwise direction, the high points 62 thereon will engage the arm 59 of the bell crank 58 and rock it in a clockwise direction. 95 This movement will be transmitted to the actuator 35 by the link 56 and yoke 50. The stud 39 on the hammer 34 is normally held disengaged from the actuator 35 by mechanism to be hereinafter described. After the 100 yoke 50 starts to move, the stud 39 is held in engagement with the actuator by a spring 65 stretched between a stud 66 on the actuator 35 and a stud 67 on the hammer 34. When a high point 62 of the cam 60 passes the 105 outer end of the arm 59 of the bell crank 58,

the spring 47 will rotate the actuator 35 rapidly in a counter-clockwise direction until the yoke 50 is stopped by a lug 70 on the base 71, of the machine. The momentum given to the hammer 34 by the spring 47 is sufficient to carry it on independently of the actuator and impel it against the type carriers 32. After the impression has been made, the hammer will be pulled back to its normal position by the action of the spring 65. This return movement will be accelerated by the reaction of the rubber platen 72. In the mechanism shown in the above mentioned application, when the hammer returns to normal it strikes the actuator 35 and stretches the spring 47, thereby causing the hammer to rebound. This rebound is in some instances sufficient to cause a second impression to be made.

A mechanism is provided in the present application to prevent the hammer from striking the actuator and thereby prevent this rebound, and will now be described. A rod 75 is carried by two arms 76 loosely mounted on the before mentioned shaft 46. One end of a link 77 is pivoted to one of the arms 76, and its other end is pivoted to an arm 78 which is loosely mounted on a shaft 79, carried by the frames 37. The arm 78 has a slot 80 cut therein, into which extends a stud 81 mounted on an arm 82 pivoted on the shaft 36. A spring 85 is provided to keep the slot 80 in proper relation with the stud 81. This spring 85 is wound around the shaft 46, and one end engages one of the arms 76, and the other end engages the base 71. The arm 82 is provided with two shoulders 83, between which the yoke member 50 is adapted to fit, as shown in Fig. 2.

When the yoke 50 is rocked by the cam 60, it will rock the arm 82, and through the stud 81 will rock arm 78. The first movement of the yoke will rock the arms 76, through the link 77, in a counter-clockwise direction, and thereby rock the rod 75 from beneath all of the hammers 34.

When the high points 62 of the cam 60 pass the outer end of the arm 59 of the bell crank 58, and the spring 47 rapidly rotates the yoke 50 and the actuator in a counter-clockwise direction as above described, the arm 82 will return the rod 75 to the position shown in Fig. 2. The rod 75 will reach its home position when the yoke 50 is stopped by the lug 70. At this time the hammer is travelling by its own momentum to take the impression. When the hammer returns to its home position the rod 75 will be in position to be engaged by the hammer and prevent it from engaging the actuator 35, thereby preventing the hammer from rebounding against the type carriers and taking a second impression.

While the form of mechanism herein shown and described is admirably adapted

to fulfill the objects primarily stated, it is to be understood that it is not intended to confine the invention to the one form of embodiment herein disclosed, for it is susceptible of embodiment in various forms all coming within the scope of the claims which follow.

What is claimed is:

1. The combination of a plurality of impression hammers, type carriers, a spring actuated means for driving each of the hammers against the type carriers for taking an impression therefrom, and a single means for arresting all of the hammers after the impression has been taken to prevent all of said hammers from engaging the spring actuated means.

2. The combination of a plurality of impression hammers, a spring actuated means for driving each of said hammers against the type carriers for taking an impression therefrom, and a single means for arresting the hammers after the impression has been taken to render said spring actuated means ineffective.

3. The combination of a plurality of impression hammers, type carriers, a spring driven actuator for each hammer, a single driving means for positively driving said actuators in one direction, and a single means interposed between said hammers and said actuators when in the home position, said interposed means being disengaged from the hammers by the driving means when the driving means begins to operate.

4. The combination of an impression hammer, type carriers, spring-actuated means for driving the hammer against the type carrier for taking an impression therefrom, and means for arresting the hammer after the impression has been taken to prevent said hammer from engaging the spring-actuated means.

5. The combination of an impression hammer, type carriers, spring-actuated means for driving said hammer against the type carriers for taking an impression therefrom, and means for arresting the hammer after the impression has been taken to render the spring-actuated means ineffective.

6. The combination of an impression hammer, an actuator therefor, said hammer being resiliently connected to the actuator when being actuated thereby, a spring for driving said actuator, means for stopping said actuator, and means controlled independently of said actuator for preventing the hammer from engaging the actuator when the hammer returns to its home position.

7. The combination of an impression hammer, a spring driven actuator therefor, a spring for engaging the hammer with the actuator when the actuator is being driven prior to actuating the hammer for taking an impression and means independent of said

actuator for preventing the hammer from engaging the actuator after the impression has been taken.

8. The combination of a plurality of impression hammers, a spring actuated actuator for each of said hammers, a spring for engaging each hammer with its actuator when the actuators are being driven prior to actuating the hammer for taking an impression, and a single means independent of said actuators for preventing all of the hammers from engaging the actuators after the impression has been taken.

9. The combination of an independently movable impression hammer, a spring-actuated driving means for said hammer, means

for positively actuating said driving means in one direction and for suddenly releasing said driving means to permit it to actuate the hammer, means for stopping said driving means after it has been suddenly released, resilient means for carrying the hammer with the driving means when said driving means is being positively actuated said resilient means permitting independent movement of said hammer after said driving means has been stopped, and means for stopping the hammer before it engages the driving means after the impression has been taken.

In testimony whereof I affix my signature.

WILLIAM W. BOWMAN.
